UNITED STATES PATENT OFFICE.

ENOS B. WILLIX, OF MOUNT VERNON, IOWA.

VOTING-MACHINE.

No. 920,706.

Specification of Letters Patent.

Patented May 4, 1909.

Application filed November 30, 1908. Serial No. 465,227.

To all whom it may concern:

Be it known that I, ENOS B. WILLIX, citizen of the United States, residing at Mount Vernon, in the county of Linn and 5 State of Iowa, have invented a certain new and useful Improvement in Voting-Machines, of which the following is a specification.

My invention is to be considered as a 10 modification and improvement of a Patent No. 864,279, for voting machines, granted myself and John Young on the 27th day of August 1907, in which there were two "lock pinions" that meshed into each other and 15 the lock was formed by certain attachments to the second pinion which were adapted to engage the first pinion at certain predetermined times and lock the further rotations of both pinions. The second pinion 20 was restored or rotated back to normal position by the separation of the two pinions when the lock was raised at the exit of the elector from the voting booth.

In my present invention there is substituted for the second pinion a sector-plate which, with the appliances connected therewith and herein after described, constitute the lock proper and which remain in operative contact with the first pinion at all 30 times. Both the pinion and the sector-plate are restored at the same time to normal or voting position by the operation of the exit lever when the elector leaves the voting booth.

35 In what it consists, its mode of construction, and its manner of operation will be described and illustrated in the following specification when taken in connection with the drawings accompanying the same and forming a part hereof in which,

Figure 1, is an end view of the lock and one of the sustaining brackets shown partly in dotted lines together with the box in which the lock is located. Fig. 2, is a front 45 elevation of two of the locks. Fig. 3, is an opposite side view from Fig. 1, of the lock removed and showing the dogs in position. Fig. 4, is a back view of the locks.

Like characters of reference denote corresponding parts in each of the drawings.

Referring to the drawings, 2 designates the face of the voting machine through which projects the voting keys 4. Through the machine longitudinally is mounted a 55 shaft 5 which is journaled in bracket plates 6

rigidly fixed to the ends of the box that carries the locks in the machine and said plates are also at intervals along in the box mounted on the shaft 5. Upon this shaft is loosely mounted pinions 8, one for each office. Each of the pinions is provided with a dove-tailed groove 3 between two adjacent cogs in which may be inserted a key 7 for the purpose of coupling the pinions together to provide for voting for candidates in a collective office. The pinions may vary in length according to the number of candidates to be elected to a given office or they may all be made of the same length and coupled together as hereinafter described and are provided with teeth or cogs 9.

Above the shaft 5 is mounted a second shaft 10 which runs parallel with the shaft 5 longitudinally through the machine. Upon this shaft is mounted a series of sector-plates 12 provided with teeth or cogs 14 which mesh into the cogs 9 on the pinions 8. These sector-plates with their removable attachments and contacts constitute the locks of the voting machine and are separated from and independent of other parts of the machine. Through the sectors 12 are holes 15 in one of which is removably inserted a screw 16 which serves as a stop for the further rotary movement of the sector for the purposes 85 presently to appear. There is also a peculiarly shaped slot 18 cut in each sector.

For the purpose of limiting the movement of the sector-plates there is provided a lever 20 one for each sector. The levers are 90 mounted on a shaft 22 which runs parallel with the shaft 10 longitudinally through the machine. The lever 20 is also provided with a lug 24 which engages and travels in the slot 18 in the sector and the lever is further provided with a shoulder or stop 25 which, when the lock is raised, as the elector leaves the voting booth, the shoulder engages a plate 26 secured against the longitudinal inner side of a side plate 28 attached to the machine and 100 by the engagement of the shoulder 25 with the plate 26 the movement of the sector or lock is directed and limited. Against the opposite inner side 30 of the casing is secured a stop 32 which is set in the same plane as the screw 16 on the sector 12 and this limits the backward movement of the sector.

Upon the shaft 10 is pivoted two dogs 34 and 35 which extend above the shaft 10 and are pivoted together by the pin or screw 36. 110

These two dogs are provided with catches 38 which are adapted to engage in between the cogs 9 of the pinion 8 and serve for the purpose of a brake to limit the rotation of the 5 pinion 8. They are set so that as one catch 38 engages between the cogs 9 the other will nearly contact with the outer end of one of the cogs 9 and as the pinion 8 is rotated the catch 38 on the dog 34 will engage the opening 10 between the cogs 9, and the catch 38 on the end of the dog 35 will contact with the outer end of one of the cogs 9. By this means, when the pinion is rotated as herein-after described, it cannot be rotated more 15 than the distance between any two cogs at any one time. The locks as thus constructed are all suspended from the shaft 10 which shaft is journaled in the bracket plates 6, and these bracket plates 6 form part of a box 40 20 in which all the locks are held.

Beneath the box 40 and through the casing 30 and plate 28 are set to reciprocate the vote keys 4 each of which is provided with an arm 44 and a handle 45 that projects out beyond 25 the casing 30. The key is further provided with a slot 46 adapted to receive a portion of the casing 30 and limit the forward movement of the key. The key is also provided with a shoulder 50, which, when the key is 30 forced into voting position, engages the side plate 28 and limits its backward movement.

The manner of operating my device is substantially as follows: It is first determined how many candidates for each office is to be 35 voted for and if only one, then the operator sets the sector-plate or lock by the insertion of the screw or lug 16 in one of the holes 15 of the sector at such place, that when the voting key is pushed in for the purpose of voting, it will not rotate the pinion and through the 40 pinion move the sector more than the distance between two cogs, when the screw 16 will come into contact with the stop 32 and prevent any further movement of that particular pinion 8 or sector 12. If it be a collective office in which there are, say, four 45 candidates to be elected for that office, then the four contiguous pinions 8 are coupled together by sliding the dove-tailed key 7 in the dove-tailed groove 3 and this holds the four 50 pinions together and they will then operate as a single pinion adapted to be engaged by four of the arms 44 of the keys on each party ticket; also the screw 16 being placed at such 55 distance from the end, in one of the holes 15, that the sector-plate can be rotated the distance of the spaces between five adjacent cogs 9. This adjustment of the screw 16 is made upon each sector used in this office. 60 If, in a collective office, where there are numerous candidates to be voted for as for instance in the election of 27 electors for president in the State of Illinois, then there will be no necessity for but two sectors, one at each 65 end of the pinion, the other sectors may be

dispensed with and where the collective office has two or three candidates then only one sector need be used for that office. Then the elector grasps the handle 45 of the vote key 4 and raises it up out of the slot 46 and pushes it inward through the casing 30 and plate 28 until the notch 50 comes in contact with the plate 28 and stops its further movement. As the key is forced inwardly the arm 44 engages one of the cogs 9 of the pinion 8 and rotates it the distance between two cogs. This movement rotates in the opposite direction the sector-plate or lock the same distance and when it is moved backward, the screw 16 will contact with the stop 32 and prevent any further rotation of the sector and then the sector is locked or locks all further voting for that office. If the elector has made a mistake and wishes to change his vote he withdraws the vote key 4 and that brings the arm 44 into engagement with one of the cogs 9 and rotates back the pinion 8 and the sector 12 to its normal position and then he can shove in another vote key from some other party as there are for each office 90 one vote key for each party for the same office. If it be a collective office for which, say four candidates for one office are to be elected then the elector can push four of the vote keys 4 on the same party or one on each party for four parties and that will rotate the pinion 8 the distance of the space between five cogs and also five cogs on the sector till the screw 16 will have come into contact with the stop 32 and prevent the voting of 95 any more keys 4. In this manner every office for which the elector has forced in the requisite number of keys will be locked by the sector against the introduction of any other key.

It will be noted that the lock 12 is common to and rotated through the pinion by one or more keys for each office and that none of the keys are connected either to the pinion or to the sector plate, and as the voter only moves 110 one key at a time and as it is moved it moves the lock one notch, there is no possibility of fraudulent voting by the voter pushing in more keys than he is entitled to nor can he in any manner render the lock inoperative by 115 the use of, or injury to the vote keys.

After the elector has chosen the parties for the various offices for whom he desires to vote and has introduced the keys corresponding with such offices, then he passes out of the voting booth and operates an exit lever which raises the box 40 together with all of its contents and attachments including the pinions 8 and sectors 12 and as it is raised the various shoulders 25 of the levers 20 engage 120 the plate 26 and this turns back the levers 20 and by the lugs 24 in engagement with the slots 18, rotates back the various sectors and pinions to their normal positions, and the box 40 with the pinions 8 and sectors 12 are 125 130

lowered to their normal position by the return of said exit lever to its normal position.

It will be seen that the pinions and sectors are always in engagement with each other whether they are in voting position or are raised for restoring them to voting position.

As the manner in which the box and the numerous locks are raised and lowered and restored to voting position is not a part of my invention, and may be done in the same manner as it is done in the above mentioned patent or by other convenient construction, it is not described in this application.

It will be observed that the elector is prevented from casting more than one vote for any candidate for any office in which there is only one to be elected but for collective offices he can cast a vote for each and every one in that collective office, selecting them from all of the various parties but can cast only the requisite number of votes for that office, and this he can accomplish by simply coupling up two or more pinions according to the number of candidates to be elected for a given office. It will further be observed that when the locks are raised and the shoulders engage the plate 26 that the levers 20 will restore all of the sectors and pinions to their normal positions whether these sectors be in a single office or a collective office, as the levers 20 by the engagement of the shoulders 25 with the plate 26 operate the lugs in the slots 18 to bring all of the sectors to the same position and open the locks ready for the next voter and as the sectors are rotated back they rotate back the pinions to their normal position.

Having now described my invention what I claim and desire to secure by Letters Patent is:—

1. In a voting machine, a lock consisting of a sector plate, means for determining the distance of the movement of the plate adjustably secured to the plate and adapted to be engaged from outside of the plate, and means adapted to engage the plate and move the plate a predetermined distance.

2. In a voting machine, a lock consisting of a sector plate provided with teeth or cogs mounted on a shaft and disconnected from the operating parts of the machine, an adjustable stop attached to the sector, a pinion mounted on a shaft and in mesh with the sector at all times, means adapted to engage the pinion and rotate it and the sector one or more cogs, means engaging the pinion to limit its rotation, and means adapted to engage the sector and rotate it and said pinion back to original position.

3. In a voting machine, a lock consisting of a plate, a stop adjustably attached to the plate, means adapted to engage the stop and arrest the movement of the plate, a lever engaging the plate, and means adapted to engage the lever and restore the plate to its

normal position after the elector has advanced the plate in the act of voting.

4. In a voting machine, a lock consisting of a plate, a pinion engaging the plate to move the plate a predetermined distance, a stop adjustably attached to the plate for limiting the movement of the plate, and means including a lever engaging the plate for restoring the sector plate and pinion to their normal position after they have been moved a predetermined distance.

5. In a voting machine, a lock consisting of a plate, means connected with the plate for determining its movement in one direction, means for moving the plate a predetermined distance, means engaging the plate to prevent the movement of the plate beyond the predetermined distance, and a lever engaging the plate to return the plate to its normal position after it has been moved.

6. In a voting machine, a lock consisting of a sector plate, means for predetermined the travel of the plate, means for rotating the plate consisting of a pinion adapted to engage the plate, a key for rotating the pinion, and a lever adapted to engage the plate and rotate the plate and the pinion back to initial position after the elector has cast his vote.

7. In a voting machine, a sector plate pivoted on a shaft and provided with a slot, a pinion adapted to engage the plate and rotate the plate, a key for rotating the pinion, and a lever adapted to engage the slot in the plate and rotate the sector plate and pinion to normal position after they have been rotated a predetermined distance in the act of voting.

8. In a voting machine, a sector plate, adapted for rotation, and provided with a slot, a stop adjustably secured in the plate, a pinion set to engage the plate and rotate it, a key for rotating the pinion, a lever adapted to engage the slot in the plate, and means engaging the lever to rotate the pinion and plate to normal position after the elector has cast his vote.

9. In a voting machine, a shaft, a sector plate mounted on said shaft, an adjustable stop attached to said sector, a pinion mounted on a shaft and in mesh at all times with said sector, means adapted to rotate the pinion in one direction and the sector in the opposite direction, and means adapted to engage the pinion and rotate it and said sector in two directions.

10. In a voting machine, a lock consisting of a sector plate provided with a slot, and pivoted on a shaft, a stop adjustably secured to the plate to predetermine the distance of rotation of the plate, a pinion engaging the plate, a vote key for rotating the pinion and by the pinion the plate, in combination with a lever pivoted on a shaft and adapted to engage the slot in the plate, with means for raising and lowering the lock, and means

engaging the lever for rotating the lock and pinion back to normal position when the lock is raised.

11. In a voting machine, a sector plate 5 provided with an irregular slot and perforations in the plate, means engaging said perforations to predetermine the travel of said sector plate, means engaging the plate to limit the rotation of the plate in one direction, means for raising the lock, a lever pivoted on a shaft and adapted to engage the slot in the plate, and means engaging the lever when the lock is lifted to operate the lever to rotate back the plate and pinion to 15 initial position.

12. In a voting machine, a sector plate pivoted on a shaft, means for rotating the plate, means for limiting its rotation to a predetermined distance, a lever adapted to 20 engage the sector plate, a shoulder on said lever, and a stop adapted to engage the shoulder on the lever and rotate the sector plate and pinion back to initial position when the lock is raised.

13. In a voting machine, means for voting for a plurality of candidates for a collective office consisting of a plurality of sector plates for each office pivoted on a shaft, means for predetermining the distance of rotations of 30 the plates, a pinion adapted to engage said plates, a vote key for each candidate on each party ticket, a lever one for each plate adapted to engage said plates, and means engaging the levers to rotate the sector plates and 35 pinion while in mesh with each other back to voting position after the elector has cast the vote for that office.

14. In a voting machine, means for voting for a predetermined number of candidates 40 for a given office and lock the office from further voting consisting of a plurality of sector plates pivoted on a shaft, an adjustable stop one for each plate to limit the rotation of said plates, a pinion adapted to engage all of said plates and rotate them a predetermined distance, vote keys one for each candidate on each party ticket adapted when operated to operate the pinion and with it the sector plates, levers one for each plate 50 pivoted on a shaft and engaging the plates, a shoulder on each lever, and means when the locks are raised to engage the shoulders on the levers and rotate back to voting position the sector plates and pinion after the 55 elector has cast the votes for that office.

15. In a voting machine, a plurality of locks consisting of plates pivoted on a shaft, a pinion adapted to engage all of the sector

plates and rotate them, independent vote keys one for each candidate on each of the 60 party tickets adapted to engage said pinion and rotate it, a lever for each plate adapted to engage each plate, and means for operating the levers to return the plates and pinion to initial position after they have 65 been moved in casting the vote.

16. In a voting machine, a sector plate pivoted to a shaft and provided with a slot, a lever pivoted on a shaft and provided with a shoulder and adapted to engage the sector 70 plate in said slot, a plate secured to the casing and adapted to be engaged by the lever, in combination with a pinion engaging the sector plate, a key engaging the pinion to rotate the pinion and with it the sector plate, 75 and means when the sector and pinion are raised to bring the shoulder on the lever in engagement with the plate on the casing and rotate back the sector and pinion to original position after they have been rotated by 80 vote key.

17. In a voting machine, means for voting for all the candidates to be elected for a collective office and lock the office against further voting in said office consisting of sector 85 plates, two or more pinions coupled together to form a single pinion adapted to engage at all times all the sectors for that office, a plurality of vote keys adapted to engage the pinion and rotate it, and means engaging the 90 sectors to rotate back the sectors and pinion while in engagement with each other to initial position after the elector has cast the votes for that office.

18. In a voting machine, a shaft, a pinion 95 mounted on the shaft, a vote key adapted to be reciprocated and rotate the pinion, means engaging the pinion to prevent the rotation of the pinion more than the space of one cog by the same key, a sector plate mounted on a 100 shaft and adapted to be rotated by the pinion with which it at all times engages, means independent of the sector and pinion and engaging the sector for determining the distance the sector shall be rotated, and means for rotating the sector and pinion while in 105 engagement with each other to normal position after they have been rotated in the act of voting.

In testimony whereof I affix my signature, 110 in presence of two witnesses.
